ABSTRACT OF THE DISCLOSURE

Sealing device with leakage gas recovery for cryogenic gas expansion reaction turbine, comprising at least two sealing systems between the chamber of the rotor and a chamber under a lower pressure separated by a chamber effecting the recovery of the leakage gas, either the exhaust gas circuit at a temperature corresponding to that between the turbine rotor and the bearings of its shaft, characterized in that the leakage gas recovery chamber is connected to a point on the circuit of the turbine exhaust gas where the latter is at a notably higher temperature than the temperature prevailing in the exhaust chamber, and preferably at a temperature equal to its own.

The present invention concerns a sealing device with leakage gas recovery for cryogenic gas expansion reaction turbine, comprising at least two sealing systems between the chamber of the rotor and a chamber under a lower pressure, separated by a chamber for the recovery of the leakage gas.

Gas reaction expansion turbines, whether they are of the centripetal or axial type, comprise a sealing device, for example a labyrinth, which is intended to reduce to the minimum the leakage of high-pressure gas towards the low-pressure chambers, either the exhaust chamber or the chamber arranged between the turbine rotor and the bearings of its shaft. A certain fraction of the high-pressure gas nevertheless infiltrates through the sealing device and becomes mixed with the cold gas at low pressure. Now, the fraction which has thus infiltrated through the sealing device has become considerably heated by friction during the course of its passage along the rapidly rotating rotor. Its mixing with the cold expanded gas of the exhaust of the turbine heats this to some extent, and therefore reduces the thermodynamic efficiency of the expansion effected in the turbine.

These leakages through the sealing device, which are not too considerable in the case of large turbines dealing with high rates of gas flow, become considerable in relative value in the case of small high-speed turbines which, for example, effect the expansion of hydrogen or helium which have already been cooled to a very low temperature, and in such cases reduce the expansion efficiency very considerably. By way of example, in the case of a small turbine of 100 m.³/h. approximately (brought to normal conditions) for the expansion of helium from 20 bars absolute to 1.3 bar absolute, effecting the cooling of the helium from 20° K. to 13° K., the leakages may reach 10 to 15% of the total flow, and may be taken to temperatures greater by several dozen degrees than that of the exhaust gas, of about 50° to 60° K.; therefore, they considerably heat the latter.

The present invention has as its object to obviate the aforesaid disadvantage, to reduce to a very small fraction the leakage rate of the high-pressure gas which becomes mixed with the low-pressure gas through the sealing device, and to approximate to the theoretical efficiency the

thermodynamic efficiency of the cycle through which passes the gas supplied to the expansion turbine.

The sealing device according to the invention is characterised in that the leakage gas recovery chamber is connected to a point on the turbine exhaust gas circuit where the gas is at a substantially higher temperature than the temperature prevailing in the exhaust chamber.

It also preferably comprises the following embodiments taken separately or in combination:

(a) The leakage gas recovery chamber is connected to a point on the turbine exhaust gas circuit where the gas is at a temperature substantially equal to that prevailing in the recovery chamber;

(b) The chamber under lower pressure is the exhaust chamber of the turbine;

(c) The chamber under lower pressure is the chamber arranged between the turbine rotor and the bearings of its shaft.

The pressure in the recovery chamber being maintained by its connection with the exhaust gas circuit near to the exhaust pressure, it will be understood that almost all the leakage flow directed towards the exhaust chamber flows by way of the recovery circuit, and that only a very small fraction becomes mixed with the cold low-pressure gas through the second sealing system.

As regards the leakage flow towards the chamber arranged between the turbine rotor and the bearings of its shaft, its recovery permits improving the thermodynamic efficiency of the overall cycle through which the gas passes, since the entire supply of cold owing to its heating from its still relatively low temperature to the ambient temperature would otherwise be lost.

If necessary, although in general this does not in practice seem to be necessary, it is possible to further reduce the flow of gas at high pressure which becomes mixed with the low-pressure gas through the sealing device, by dividing the latter into three separate sealing systems which are separated by two recovery chambers, or in a more general manner into n separate sealing systems which are separated by $(n-1)$ recovery chambers, each of the recovery chambers being connected to a point on the exhaust gas circuit at a temperature corresponding to that of the fraction received in this chamber.

By way of a non-limitative example and with reference to the figure shown in the accompanying drawing, a description will now be given of the sealing device according to the invention between the rotor chamber and on the one hand the exhaust chamber and on the other hand the chamber arranged between the rotor and the gas bearings of the shaft, of a centripetal turbine with a closed rotor for helium expansion.

The expansion turbine is connected to an inlet conduit for the gas under pressure 1, which opens into the annular pressure admission chamber 2. This supplies fixed bladings 3 forming the distributor; on issuing therefrom, the gas enters the mobile bladings 4 of the turbine rotor 6 which rotates in the rotor chamber 5. The turbine rotor, supported by the shaft 7, comprises an annular exhaust aperture 8 opening into the exhaust chamber 9. The pressure prevailing in the rotor chamber 5 is greater than the pressures in the exhaust chamber 9 or the chamber 22 arranged between the rotor and the bearings of the shaft (not shown). Therefore, it is necessary to provide a sealing device between the mobile rotor and the body of the turbine. This device comprises two portions on either side of the rotor, each divided into two sealing systems, respectively 12A, 12B and 13A, 13B constituted by labyrinth. Between the sealing systems 12A and 12B there is arranged a recovery chamber 14 in which the gas under pressure arrives which has infiltrated along the rotor and through the sealing system 12A. Conduits 16 and then 18 discharge the gas from this chamber towards a point 19

on the exhaust gas circuit where the said gas is substantially at the same temperature.

Arranged between the sealing systems 13A and 13B is a second recovery chamber 15 into which arrives the gas under pressure which has infiltrated along the rotor and through the sealing system 13A. Conduits 17 and then 18 effect the discharge of the gas from this chamber towards the point 19 on the exhaust circuit which is at the same temperature. It will be noted that if the leakage gas arriving at the chamber 15 were at a temperature different from the leakage gas arriving at the chamber 14, it could be directed by a different conduit towards another point on the circuit of the exhaust gas.

The exhaust gas of the turbine is partly heated by a device for maintaining a low temperature, represented diagrammatically by a heat exchanger 20, in counter-current with a warmer fluid, and then heated again in the exchanger 21 in counter-current with the gas under pressure. Then, after addition of leakage gas from the conduit 18 at 19, it is heated to the ambient temperature and re-cycled to the intake side of the compressor (not shown) which again brings it to the admission pressure for the turbine, and then re-cycled by the conduit 23 and the exchanger 21 to the conduit 1 for supplying the turbine.

It will be understood that various modifications may be made in the sealing device which has just been described without departing from the framework of the invention.

In particular, the expansion turbine may be axial and not centripetal; it may comprise several stages instead of only one. The heating circuit for the exhaust gas may be different. The circuit gas may be different, for example air, nitrogen or neon.

What I claim is:

1. In a closed cycle cryogenic gas expansion-compression cycle in which compressed gas flowing in a closed circuit enters an expansion reaction turbine comprising a rotor in a rotor chamber and is expanded therein and is discharged to a chamber under lower pressure than the pressure in the rotor chamber at a lower temperature than the temperature in the rotor chamber and is recompressed and recirculated to the turbine and enters the turbine at a temperature and pressure substantially higher than the temperature and pressure in the dis-

charge chamber; the improvement comprising at least two sealing systems between the rotor chamber and a chamber under lower pressure than the rotor chamber, said at least two sealing systems being separated by a recovery chamber, and conduit means for conveying gas from said recovery chamber to a point in said closed circuit where the temperature is at a substantially higher temperature than the temperature in said discharge chamber.

2. Apparatus as claimed in claim 1, said chamber under lower pressure being said discharge chamber.

3. Apparatus as claimed in claim 1, said turbine rotor having a shaft supported by bearings, said chamber under lower pressure being disposed between the turbine rotor and said bearings.

4. In a method for improving the efficiency of a cryogenic gas expansion reaction turbine in which gas circulates in a closed circuit through the turbine in which it is expanded and cooled and is subsequently warmed and recompressed and reintroduced into the turbine, the turbine having a rotor disposed in a rotor chamber and discharging gas to an exhaust chamber, the leakage of gas from the rotor chamber being impeded by at least two sealing systems arranged serially in the path of gas leakage; the improvement comprising withdrawing gas leakage from between a pair of said at least two sealing systems and reintroducing said withdrawn gas into said closed circuit at a point in said circuit where the temperature of the gas is substantially higher than the temperature prevailing in the exhaust chamber.

5. A method as claimed in claim 4, the temperature in said closed circuit at said point of reintroduction being substantially the same as the temperature of the withdrawn gas.
